FIG. 3

FIG. 4

FIG. 5

FIG. 1 is a perspective view of a lavatory fixture unit embodying our new design;

FIG. 2 is a side elevational view thereof;

FIG. 3 is a top plan view thereof;

FIG. 4 is a front elevational view thereof;

FIG. 5 is a rear elevational view thereof; and

FIG. 6 is a perspective view of a modified form of the lavatory fixture unit shown in FIG. 1.

The broken line representation of a portion of a counter top in FIGS. 1 through 6 is for purposes of illustration only.

I claim:

The ornamental design for a lavatory fixture unit, substantially as shown and described.
